UNITED STATES PATENT OFFICE

WILLIAM WALTON VENABLE, OF CHARLESTON, WEST VIRGINIA

UNLOADING APPARATUS

Application filed September 20, 1926. Serial No. 136,653.

This invention relates to unloading apparatus, and more particularly to an apparatus for unloading coal and other loose material from barges.

5 An important object of the invention is to provide a bucket adapted to traverse a barge to scoop material therefrom, and to provide novel operating means for the bucket to effect the scooping action and to convey the bucket to a suitable discharge point.

10 A further object is to provide an apparatus of the above mentioned character wherein suitable means are provided for supporting the bucket for sliding action to the point of discharge.

15 A further object is to provide an inclined shore ramp adapted to be connected with the barge by an apron which is adapted to swing to accommodate itself to varying positions of the barge and varying tides, the scooping bucket being adapted to slide through the apron and ramp to the point of discharge.

20 A further object is to provide novel supporting and conveying means for the bucket whereby the latter is adapted to be lowered into the barge to scoop material therefrom and to slide through the apron and ramp to the discharge point, the conveying means being adapted, if desired, to elevate the bucket 25 after the material has been discharged therefrom whereby it may travel back to the starting point while suspended in the air above the conveyor and above the ramp and apron.

25 A further object is to provide an apparatus 30 of the character just mentioned having novel discharge means whereby the bucket is adapted to be tilted to a dumping position and supported in such position until it is empty.

35 A further object is to provide novel conveying means for the scooping bucket including a supporting cable which is adapted to support the scooping bucket in an elevating position above the barge or in a lower scooping position, and to provide a pulling cable which is adapted to convey the bucket from scooping position to dumping position.

40 Other objects and advantages of the invention will become apparent during the course 45 of the following description.

In the drawings I have shown several embodiments of the invention. In this showing:

Figure 1 is a side elevation of the apparatus in operation, parts being broken away, 55

Figure 2 is a plan view,

Figure 3 is a section on line 3-3 of Figure 1,

Figure 4 is a similar view on line 4-4 of Figure 1, 60

Figure 5 is a detail perspective of the scooping bucket,

Figure 6 is a detail section on line 6-6 of Figure 2,

Figure 7 is a fragmentary perspective 65 view of the adjustable sheave supporting means,

Figure 8 is a detail section on line 8-8 of Figure 1,

Figure 9 is a similar view on line 9-9 of 70 Figure 2,

Figure 10 is a side elevation of a modified form of the apparatus, parts being shown in section, and,

Figure 11 is a plan view of the same. 75

Referring to the drawings the numeral 10 designates the shore bank suitably supported as at 11 in the usual manner. A suitable discharge platform or the like 13 is provided upon which the conveyed material is adapted 80 to be dumped. Suitable foundations 14 are arranged on the bank and are provided with upwardly extending columns 15 supporting a platform 16. A suitable sheave post 17 is arranged on the platform and is braced as at 85 18. Sheaves 19 and 20 are carried by the post 17, and cables 21 and 22 are passed around these sheaves.

At any suitable point on the bank, winding drums 23 and 24 are provided, about which 90 the cables 21 and 22 are adapted to be wound, respectively. The drums may be driven by a suitable hoisting engine or the like, as will be apparent.

A second foundation member 26 is arranged 95 as shown in Figure 1, and this member is adapted to be connected to the upper end of the columns 15 by braces 26'. An inclined ramp 27 is arranged between the columns 15 and braces 26'. This ramp includes suitably 100

braced side walls 28 and a bottom 29. The upper end of the ramp is provided with a discharge opening 29' in which the scooping bucket is adapted to be lowered in a manner to be described. Inwardly of the opening 29', a pair of depending angle irons 30 are arranged, and a plate 31 is secured to these angle irons as shown in detail in Figure 8. A pair of arcuate angle irons 32 are arranged 10 at the upper end of the open end 29, for a purpose to be described. The upper end of the ramp is secured to the platform 16 by braces 33 and 34, and the ramp is also suitably supported by the braces 26 by depending braces 35. Horizontal braces 36 also are secured to the upper end of the foundation 26 and to the ramp as shown in Figure 1. The side walls of the ramp are provided near their lower ends with a plurality of openings 37 for 20 a purpose to be described.

Referring to Figures 1, 2 and 6, the numeral 38 designates an apron including suitably braced side walls 39 and a bottom 40. A depending stop member 41 is carried by the 25 lower end of the apron as clearly shown in Figure 6, the lower end of the apron when in operation, being supported upon one end of a barge 42. The stop 41 is adapted to properly position the barge with respect to the 30 apron as will be apparent. The upper end of the apron is provided with an extension 43 at each side, and a bolt 44 passes through each extension and one of the openings 37 whereby it will be apparent that the apron is pivotally 35 connected to the ramp. The bolts 44 may be arranged in selected openings 37 for a purpose to be described. Any suitable means may be provided for elevating the lower end of the apron when a barge is to be moved out of 40 operative position and a loaded barge brought into position. As shown in Figures 1 and 3, suitable supports 45 are arranged on posts 46 and are provided with chain blocks 47. These 45 blocks are provided with the usual chains 48 secured at one end to the lower portion of the apron whereby movement of the chain is adapted to raise and lower the lower end of the apron.

As previously stated the barge 42 is adapted 50 to be brought into the position indicated in Figure 1 with one end thereof arranged beneath the lower end of the apron. The opposite end of the barge may be provided with a pair of upstanding posts 49 connected by a transverse beam 50. As shown in Figure 7, I prefer to employ an I-beam 50 having a series of openings 51' in one base thereof to selectively receive a bolt 51 carried by a sheave 52. A nut 53 is arranged on the end of the bolt 50. The construction just described is provided to permit the sheave 52 to be adjusted in different positions with respect to the width of the barge and it will be apparent that any suitable form of adjusting means 65 may be employed. At its forward end, the

barge 42 is provided with an inclined slide 54 suitably supported by braces 55. The upper end of the slide is preferably provided with a metal plate 56 arranged slightly above the line of the bottom 40, for a purpose to be described. 70

The scooping bucket adapted to be used in connection with the apparatus is indicated as a whole by the numeral 56 in Figure 5 of the drawings. This bucket includes sides 57 and a solid bottom 58. The forward end of the bucket is open as shown at 59 and is closed at its rear end as at 60. A transverse brace 61 is secured across the top of the forward end of the bucket, and a vertical connecting member 62 extends from the brace 61 to the bottom of the bucket and is provided with a series of openings 63. A pair of connecting links 64 are pivotally connected to the member 62 by a bolt 65 which passes through one of the openings 63. The forward ends of the links 64 are connected by a bolt 66 to an eye 67 secured to the end of the cable 21. The rear wall 60 of the bucket is provided with an upstanding brace 68 in which is supported a sheave 69, and the cable 22 passes under this sheave. An auxiliary sheave 70 is adapted to maintain the cable 22 in proper position in the sheave 69. The end of the cable 22 is secured to the rear end of the bucket as at 71. 80

Between the sheave 19 and the eye 67, the cable 21 passes over a sheave 72 supported upon the forward end of the platform 16. The cable 22 passes around a sheave 73, also supported upon the platform 16, and from this sheave the cable 22 passes under the sheave 69, thence over the sheave 52, the end of the cable 22 being secured to the bucket 56 at 71, as previously stated. 90

In Figures 10 and 11 of the drawings I have shown a somewhat modified form of construction particularly adapted for transferring material from a barge to trucks, tram cars, or to another vessel. In the modified form of the invention the barge 42 is provided with the same operating elements previously described, and these elements need not be referred to again in detail. As shown, the ramp is eliminated, and an apron 74 is employed. 100 This apron is pivotally connected as at 75 to a supporting structure 76. The apron is similar in construction at its lower end to the apron 38 previously described, while the upper end of the apron 74 is provided with means for tilting the bucket to dumping position as indicated at the upper end of the ramp 27. This means includes the depending angle irons 76', corresponding to the angle irons 30, and the angle irons 77 corresponding to the angle iron 32. In the form of the invention shown in Figures 10 and 11, material is adapted to be discharged into a hopper 78 carried by the supporting structure 76, and tram cars 79 may be brought into position be- 110 120 130

neath the hopper, as will be obvious. The modified form of the construction also includes cables 80 and 81 corresponding respectively to the cables 21 and 22. The cable 80 passes over sheaves 82 and 83 arranged on the upper end of the supporting structure 76. After passing over the sheave 83, the cable 80 passes around the sheave 69 of the bucket, thence to and around the sheave 52, the end of the cable 80 being secured to the bucket as at 71, as previously described. The cable 81 passes over a sheave 84 also arranged on the supporting structure 76, the end of this cable being secured to the forward end of the bucket in the manner previously described. The cables 80 and 81 pass over drums 85 and 86 adapted to be driven by a suitable hoisting engine 87.

Any suitable means may be employed for supporting the lower end of the apron 74. As shown, I may employ a support 88 having upstanding arms 89 connected by a cross piece 90. The upper end of the support 88 may be suitably connected to the supporting structure 76 by a cable or the like 90'. Chain blocks 91 are carried by the support 88 and are adapted to operate chains 92 connected at their lower ends to the lower end of the apron 74. If desired, the stops 41 at the lower ends of the apron 38 may be replaced by a cross piece 92, as shown in Figures 10 and 11, and rods or cables 93 may connect the cross piece 92 with posts 94 carried by the barge whereby the latter may be secured in proper position.

The operating elements of the apparatus shown in Figure 10 are indicated as being mounted upon a scow 95 and it will be apparent that this mechanism may be supported upon any suitable form of structure such as a dock.

The operation of the apparatus is as follows:

A loaded barge is brought to the position shown in Figure 1 with one end thereof arranged adjacent the stop 41. The barge may be anchored in position by any suitable means as will be apparent. The chain blocks 47 are then operated to lower the end of the apron to operative position whereupon the sheave 52 is secured in position. The bucket will be supported by the cable 22, and by slackening off the cable 21 and pulling the cable 22, the bucket may be moved to the dotted line position indicated at the left hand end of Figure 1. The cable 22 is then slackened as shown in the dotted line position referred to, whereupon a pull exerted upon the cable 21 will cause the bucket to swing thus causing the open forward end thereof to dig into the material in the barge. The cable 21 is wound upon its drum whereby the bucket will be moved to the forward end of the barge. The cable 22 may be suitably slackened to permit the bucket to travel across and through the upper portion of the material in the barge until it

strikes the slide 54, whereupon it will be supported upon the slide with the bottom 58 in contact therewith. The operator continues to transmit a pull to the cable 21, which causes the bucket to travel from the slide to the apron, thence throughout the length of the apron to the ramp 27. The bucket then travels up the ramp until it reaches the open portion 29 of the ramp whereupon the cable 21 is slackened to permit the forward end of the bucket to drop by gravity to the position shown in solid lines in Figure 1. The bottom of the bucket then will contact with the plate 31, and the bucket will be supported by the lower ends of the arcuate angle irons 32. The latter angle irons are curved as shown to permit the bucket to swing downwardly to dumping position. It will be apparent that when the bucket is arranged in the dumping position, the material will be discharged therefrom. The cable 22 is then wound about its drum, thus elevating the bucket and the cable 21 slackened off, whereupon continued winding of the cable 22 will cause the bucket to move downwardly to its initial position. The position of the sheave 52 may be varied across the barge by removing the bolt 51 and changing it to different openings 51'. Thus it will be apparent that the material throughout the length and width of the barge readily may be unloaded.

The unloading of barges generally is accomplished by the use of clam shell buckets which leave a considerable portion of material in the barge. With the use of the present device, the barges may be more completely emptied and no damage will be done to the sides and decks of the barges. The operation of the form of the invention shown in Figures 10 and 11 is substantially the same so far as the operation of the cables is concerned. The bucket is drawn throughout the length of the barge until it contacts with the slide, whereupon it will assume the position previously described with the bottom of the bucket contacting with the slide to be supported thereby. Continued pulling of the cable 21 will cause the bucket to travel through the length of the slide and apron 74 until it reaches the dumping position whereupon the cable 21 is slackened to permit the bucket to be dumped by gravity. In either form of the invention it will be apparent that the lower ends of the apron may be elevated by the chain blocks referred to when an emptied barge is to be removed and a loaded barge placed in position for unloading.

The slide plate 56' is arranged slightly above the line of the bottom of the apron to facilitate the sliding action of the bucket from the slide to the apron, and similarly it will be apparent that the elevation of the upper end of the apron above the lower end of the ramp is adapted to facilitate the sliding of the bucket between these members.

5 The bolts 44, arranged in the openings 37, provide a pivotal connection whereby the lower end of the apron may be swung upwardly from operative position when desired and to compensate for varying water and barge levels. The bolts 44 may be arranged in selected openings 37, to compensate for excessive changes in the heights of barges due to changes in water levels.

10 It is to be understood that the forms of the invention herewith shown and described are to be taken as preferred examples of the same and that various changes in the shape, size and arrangement of parts may be resorted to without departing from the spirit of the invention or the scope of the subjoined claims.

15 I claim:

1. A conveyor trough comprising a substantially U-shaped inclined body having an opening adjacent its upper end, a depending support carried by said trough within the lower portion of said opening and adapted to support a conveyor bucket therein, and a pair of angular members arranged at the upper limit of said opening and having their lower ends curved inwardly toward said support.

2. A conveyor trough comprising an inclined body, a depending support arranged at the upper end of said body and adapted to support a conveyor bucket, and a member arranged at the upper end of said body and curving inwardly toward said support whereby the lower end of said body is spaced from the lower end of said support a distance less than the height of the conveyor bucket.

3. In combination, an open topped cargo carrier, a cargo receiving structure mounted wholly independent of said carrier, a trough arranged between said carrier and said structure, a scraping element movable between said carrier and said structure, and means for operating said scraping element whereby it will be in constant engagement with said trough during its travel throughout the length of the trough, said trough comprising a lower inclined apron and an upper inclined ramp, the adjacent ends of said apron and said ramp being pivotally connected to each other, the upper end of said ramp being provided with a depending discharge opening.

4 In testimony whereof I affix my signature.

55 WILLIAM W. VENABLE.
